UNITED STATES PATENT OFFICE.

EDWARD S. SAVAGE, OF ROCHESTER, NEW YORK.

ART OF PRINTING.

Application filed December 15, 1919. Serial No. 345,095.

To all whom it may concern:

Be it known that I, EDWARD S. SAVAGE, a citizen of the United States, and resident of Rochester, in the county of Monroe and State of New York, have invented certain new and useful Improvements in the Art of Printing, of which the following is a specification.

The present invention relates to a method of preparing typewritten matter for photo-engraving and to a form used in such method, an object of this invention being to provide for the alignment of the last letters of the typed lines so that matter printed from the photo-engraving will appear symmetrical.

To these and other ends, the invention comprises, in addition to the method, certain parts and combinations of parts, all of which will be hereinafter described, the novel features being pointed out in the appended claims.

In the drawings:

Fig. 1 is a fragmentary view of one form of a typed sheet made in accordance with this invention;

Fig. 2 is a fragmentary top view of a form through which the end characters of the typed lines are brought into alignment by separating the word pieces, the form being shown as associated with a justifying mechanism for the word pieces, and the word pieces being shown in the position they occupy before the operation of the justifying mechanism;

Fig. 3 is a fragmentary view of the opposite end of the form and the justifying mechanism, the latter being shown in the position which it occupies after the shifting of the word pieces.

Fig. 4 is a section on the line 4—4, Fig. 3;

Fig. 5 is a sectional view through the form after the word pieces have been secured in their shifted positions;

Fig. 6 shows in plan and in side elevation, fragmentary views of the sheet strips;

Fig. 7 is a fragmentary view of another typed sheet constructed under this invention;

Fig. 8 is a section through the typed sheet shown in Fig. 7;

Fig. 9 is a fragmentary plan view of another form constructed in accordance with this invention, the typed sheet strips being shown in the positions which they occupy before expansion;

Fig. 10 is a fragmentary view of the opposite end of the form shown in Fig. 9 showing the expandable typed strips in the position which they occupy after expansion; 60

Fig. 11 is a section on the line 11—11, Fig. 10;

Fig. 12 is a fragmentary view of one end of another form of the invention showing the word pieces on a form with a justifying 65 mechanism associated with the form;

Fig. 13 shows in side elevation the devices illustrated in Fig. 12, parts being shown in section;

Fig. 14 is a section on the line 14—14, 70 Fig. 12;

Fig. 15 shows in plan and side elevation, one of the spring pawls used in the adjusting mechanism;

Fig. 16 shows in plan and side elevation, 75 a fragmentary view of a sheet on which the matter is typed; and

Fig. 17 is a perspective view of one of the extensible line supports of still another embodiment.

Referring first to the embodiment shown in Figs. 1 to 6, 1 indicates a sheet of paper or similar material on which the matter from which the photo-engraving is to be made, is typed. The typewriting machine 85 which is employed for typing the matter preferably has a type bar formed with a cutter adapted, at intervals, to produce slits 2 preferably between the different words, these slits being of sufficient length to extend 90 at least midway between the spaces between the different lines. It is preferred also to provide numbers or characters 3 at the end of each typed line. The sheet in this form may also be provided with short slits or cuts 95 4 preferably of arcuate form to provide openings for a purpose to be hereinafter set forth, these openings being equidistantly spaced from the last letter of their respective lines. Opposite edges of the sheet may 100 be provided with two series of aligned openings 5 and 6, one opening in each series aligning with one of the typed lines.

The sheet of this embodiment and in the condition above set forth is applied to a 105 plurality of parallel extensible line supports of a form. These line supports each comprise a strip 7 of rubber or other suitable elastic material, the strips being arranged in parallel relation upon the frame 8 of the 110 form. In this instance, this frame 8 is rectangular and has detachably secured on its

opposite longitudinal sides, a plurality of hooks or clips 9, each clip having an upwardly projecting prong 10. The elastic strips are anchored on these prongs or projections and the typed sheet after cutting off the sheet on the line 11 is then adhesively secured to the strips, the openings at the edge of the strips being fitted over the projections 10 on the clips, so that the spaces 10 between the elastic strips will align with the spaces between the lines on the typed matter, a distance along the right hand side of the typed sheet being left free from the strips.

After the strips have been adhesively set 15 cured as set forth, a cutting device is employed which cuts the sheet between the typed lines. If desired inelastic pieces 12 may be adhesively secured at the left hand side of the elastic strips. When the sheet 1 20 is cut between the typed lines, these cuts intersect the cuts 2 between the words and in this way each typed line will be formed by a plurality of separate pieces, each of which in this instance, contains a single word all 25 though it will be apparent that it is not necessary that each separate piece shall contain a single word. It will also be noted that the first piece of each line is inelastic so that the first letter of each line except the line which 30 forms the beginning of a paragraph, will be held in a fixed relation throughout the column in order that, when the typed line is justified, the position of the first letter will not be shifted and the column will be aligned 35 along the left hand side. The justifying of the typed line in order that the last letter of each of the lines may be brought into alignment is effected by shifting the pieces forming each line, this shifting varying in the 40 different lines, depending upon the amount the last letter in any one line is situated from a given line which is to form the right hand side of the column.

The shifting of these line forming pieces may be effected in any suitable manner. It is preferred however, to provide a justifying mechanism which will operate upon all the lines at one operation and shift such pieces the desired amount. This mechanism comprises in the embodiment shown in Figs. 1 to 6, a frame 13 having a seat 14 for the frame 8. At one side of this frame 13 a plurality of detents or hooks 15 are mounted upon a rock bar 16 which is journaled at its ends in a slide or carriage which operates on the frame 13. This slide or carriage comprises two blocks 17 connected by a rod 18 and moved back and forth through the medium of a crank handle 19, which is secured to one 60 end of a rock shaft 20 journaled in the frame 13 below the slide. The rock shaft 20 carries two arms 21 which by links 22 are connected to the end pieces 17. The relative movements of the word pieces are effected by swinging the hooked devices 15 from the

position shown in Fig. 2 to a position where the hooks will lie on the word pieces forming the typed line. The crank handle 19 is then turned to the left, thus shifting the hooks to an extreme position over the typed 70 lines. The movement of the crank handle 19 in the opposite direction will cause the hooks or detents to ride over the pieces forming the typed line until each hook enters one of the openings 4 formed in the last word 75 piece of each line, after which this piece will be shifted and through the elastic connections between the pieces forming each line, all of the pieces will be shifted until the last letters of the lines are brought into alignment in the manner shown in Fig. 3 of the drawings.

After the positions of the word pieces are reached, the last word piece of each line is anchored on the hook at the right hand side 80 of the line, any suitable means being employed for this purpose. A desirable means for simultaneously anchoring all of the end word pieces of the lines comprises a rubber strip 23 secured in a grooved bar 24 which is 85 supported at opposite ends by arms 25 mounted to turn on the rocking bar 16 relatively to the hooks 15. A spring 26 normally holds the rubber strip 23 out of contact with the hooks 15 and in spaced relation thereto 90 as shown in Fig. 4 of the drawings, this spring permitting the rubber bar to move downwardly so as to cooperate with the hooks 10 and the detents 15 being provided with slots 27 through which the hooks 10 95 may be passed, thus securing the last piece in each line to a hook 10 at the right hand side of the frame 8, in the manner shown in Fig. 5 of the drawings, the elastic strip 7 being bulged in the manner shown in Fig. 5. 100 When this has been accomplished, the frame 8 is removed from the justifying mechanism and is then ready for photographing in the manner well-known in producing the photo-engravings, as each of the lines is connected 110 to the frame independently of the other lines by detachable clips, it is apparent that any one of the lines may be removed in the event that an error is found in the line. It is apparent that the last letter at the end of a 115 paragraph is not shifted and in this instance such typed line will not be provided with a cut 4.

In the embodiment shown in Figs. 7 to 11 inclusive, the typed matter is written upon a 120 sheet 28 of elastic material such as rubber. This sheet of rubber has along its opposite edges, two series of perforations 29 and 30. It also has near the series of openings 30, a number of characters 31 to indicate the lines 125 on the sheet. Secured to the rear side of the sheet along its opposite edges are two inelastic strips 32 and 33 these inelastic strips being adhesively secured to the sheet 28 in order that the sheet will not stretch at these 130

points. The inelastic strip 33 and the sheet 28 are provided with coincident arcuate slots 34 situated at different distances from the edges of the sheet but at equal distances 5 from the ends of the typed lines.

The form used in connection with this sheet comprises in this instance a rectangular frame 8^a and a plurality of metallic strips 35 having metal clips 36 at their ends 10 adapted to engage detachably about the frame 8^a and having also adjacent the right hand side of the frame, longitudinal slots 37. Hooks 38 and 38^a are provided near opposite ends of the strips 35, and the hooks 15 38 passing through the openings 29 in the sheet 28. After the sheet has been arranged upon the strips, a cutting mechanism is employed for cutting the sheet between the typed lines so that a number of elastic or 20 extensible strips of typed lines 28^a are provided. When the strips containing the typed lines have been thus prepared, the frame 8^a is fitted to the justifying mechanism shown in Figs. 2, 3 and 4 and the 25 strips are stretched or adjusted in the manner described with reference to the embodiment shown in Figs. 1 to 5. When the typed lines are adjusted, the elastic portion between the inelastic portions 32 and 33 is 30 stretched an amount sufficient to bring the last letter on each line support in alignment with the last letters on the other line supports.

In the embodiment of the invention shown 35 in Figs. 12 to 16, the matter to be photo-engraved is typed upon an ordinary sheet of paper such as shown at 90 in Fig. 16 and this sheet is provided preferably between each word with a number of slits 2^b 40 such slits being formed with a curved portion 2^c between their ends and the slits being of such length that they will intersect a line cut midway between the typed lines.

The sheet is placed upon supporting means consisting of a plurality of bars 40 resting upon the side bars of a frame 8^b and having notches 41 adjacent opposite ends to receive the upper edges of the side bars, the ends of the bars projecting beyond the side bars to provide finger pieces 42 through which the bars may be removed or fitted to the rectangular frame 8^b. In order to detachably hold the bars 40 to the frame, depending spring latches 43 are provided 55 on the under side of the bars for engaging at their free or lower ends in longitudinally extending grooves 44 formed on the inner faces of the sides of the rectangular frame 8^b. The bars 40 are provided with 60 longitudinally extending grooves or channels 45 in their upper faces and they are also provided, each near its left hand end with a pin or projection 46. These pins or projections are adapted to be passed 65 through the series of openings extending

along the left hand side of the sheet, each opening in the sheet being aligned with a line of type on the sheet, thus causing the line to be properly positioned over the bar 40. The tops of the bars on opposite sides 70 of the channels are preferably coated with slow drying glue or other sticky substance, which while holding the pieces into which the sheet is cut against accidental displacement, will permit the relative movement of 75 the pieces as will be hereinafter more particularly pointed out.

After the sheet has been applied to the bars, it is cut between the lines so as to intersect the slits 2^b, thus cutting the sheet 80 into a number of different pieces, each piece containing one word. The first word of each line will be held against movement, due to the fact that it is not separated from the opening at the end of the line. The other pieces forming each line are shifted in the direction of the line so as to cause the last letters of the different lines to be aligned at the right hand side of the form. With 85 the end in view of confining the pieces to movement in the direction of the length of the bars, a frame made up of a number of guide strips is provided. Each of these guide strips has a reduced lower portion 47 which fits between the bars 40 and a larger upper portion 48 which projects above the bars, for a purpose which will be herein-after described. The reduced portions act 90 as guides for the pieces of the sheet to confine the pieces to movement in the direction of the length of the bars.

A justifying mechanism which may be used for separating the pieces in the line so as to bring the last letters of the lines in alignment comprises a base frame 49 formed 100 to receive the frame 8^b and carrying a plurality of piece shifting devices 50, one set for each line of typed matter, these piece shifting devices being preferably in the form of slides formed with resilient portions 50^a and guided in the slotted sides of the frame 51 to one side of the rectangular frame 8^b, the slides being arranged in a column, one above another for each line. The slides in each column have downwardly turned portions 52 at one end overlapping 110 the downwardly turned portions in the same row, the length of these downwardly turned portions gradually decreasing from the uppermost slide to the lowermost slide and the extreme ends of the downwardly turned portions being extended laterally at 53^a and having hooks or projections 53 thereon, the laterally extending portions 53^a on the uppermost slide being below such portions on 115 the other slides in the same column so that the hooks or projections on the slides have their positions progressively at different heights with reference to the lowermost projection. These projections are adapted 120

to successively enter between the pieces forming a line of typed matter, the tongues 2^e being depressible to permit the entrance of the projections between the pieces. This 5 movement of the projections 53 between the pieces is effected by shifting the slides 51 to the right until the projection on the slide reaches its proper position after which the others proceed without it until the movement of all the slides is discontinued.

10 The movement of the slides is effected preferably by shifting the frame 51 on the base frame 49 to one side of the frame 8^b. This movement of the frame 51 may be effected by a shaft 54 having a pinion 55 thereon meshing with a rack 56 which is secured to the slide carrying frame 51, the movement of the frame 51 being continued until all of the slits at the ends of the words 15 20 have received one of the projections on the slides. The slides are guided during this movement by the upper portions 48 of the guide strips.

25 After the slides have been shifted to fill up all the slits, the slides are then moved different amounts, the one nearest the right hand side of the sheet being moved to bring the end letter in that word in alignment, the other being moved proportionately less depending on the number of cuts 2^b, the movement of each word being such as to leave the space between the words in that line equal. The amount of movement of the different 30 35 slides is determined by a stop or shoulder 57 at the end of the groove or channel 45 which is engaged by the projection 53 on that slide which enters the notch at the end of the last word in the typed line.

With the end in view of effecting the differential movement in the slides, each column of slides may be operated through a swinging member 58 pivotally mounted on the rod 59 which is supported in spaced bearing pieces 60 arranged in a slot in the 40 45 top wall of the frame 51. The swinging members 58 are preferably in the form of two spaced pieces connected at their upper ends by a cross piece 61 and slotted at 62 so that they may move longitudinally on the rod 59, the two spaced pieces straddling one 50 55 column of slides 50 and being connected below the slides by a cross piece 63. Operating between the slides 50 are a number of pawls 64, each pawl having oppositely extended spring arms 65 which bear upon the upper surfaces of the slides 50, such upper surfaces being toothed at 66 for engagement by the pawls. The pawls also have laterally extending fingers or projections 67 which 60 65 operate in the slots of the two parts of the swinging member 58. Between the two parts of each swinging member 58 a guide 68 is mounted, said guide being pivotally mounted on its lower end on the rod 59 and having its upper end guided through the con-

nection 61. A coil spring 69 surrounds this guide and at its upper end abuts the connection 61 and at its lower end abuts the shoulder 70. This spring acts on the swinging member 58 in a direction to elevate said member in order to bring the cross piece 63 in engagement with the under side of the lower slide 50 thus causing said column of slides to be elevated as a whole and the top surfaces on the slides to be engaged by the 75 pawls 64.

To the end that this swinging member 58 will not move under the action of the spring 69 so as to provide for the relative movement between the slides during the movement of the frame 51, the swinging member is locked in its lowermost position and to this end, hooks 71 are provided on the lower ends of the swinging member for engaging in a groove 72 on a transversely extending 80 85 bar 73 which lies below all of the columns of slides 50.

The movement of this swinging member may be effected in any suitable manner. In this instance there is provided an operating 90 member 74 in the form of a bail pivoted at 75 to two swinging links 76 which are in turn pivoted at 77 to the top of the sliding frame 51, the bail having projecting portions 78 near its pivot 75 for cooperating 95 with studs 79 on the links 76. The links 76 are connected by a rod 80 on which are anchored a number of helical springs 81, these springs extending from said rod to the 100 swinging member 58, being connected to the latter at 82 and forming resilient connections between the operating member and the swinging members 58.

After the frame 51 has been shifted away from the frame 8^b in order to cause the 105 projections 53 on the slides 50, to enter between the different word pieces, the operating member 74 is depressed so that the bar 83 thereon will engage with projections 84 formed on the swinging member 110 115 58, thus causing the hooked portions 71 on the swinging members 58 to be disengaged from the cross piece 73. With this disengagement, the springs 69 will move the swinging members 58 on their fulcrums 59, 115 thus bringing the cross piece 63 against the lower slide 50 of each column and elevating the column as a whole so that each slide 50 is interlocked with its swinging member 58 through its pawl or detent 64. The operating bail 74 is now swung upwardly and through the springs 81 swings the members 58 upon the pivots 59, thus transmitting to the slides 50 the movement of the swinging member. The movement of the swinging member is continued until the projection 53 which extends through the slit or opening at the end of the line, cooperates with the stop 57 formed on the strip or bar 40, thus holding the swinging member against 120 125 130

any further movement under the action of the operating bail 74, the spring 81 thereafter yielding until all of the operating members 58 have been stopped by the stops 57 at the ends of their respective typed lines. When this position is reached, all of the letters at the ends of the different lines are brought into alignment, due to the fact that the stops 57 are arranged in alignment. The justifying mechanism may then be elevated through the handle 85 to swing the frame 51 about the shaft 54 as an axis. The justifying mechanism may be re-set by bringing the cross piece 83 into engagement with the projections 84 on the swinging members 58 in order to move the hook end 71 of the swinging members below the cross piece or bar 73. After this has been accomplished the slides or bars 50 may be brought by hand to the position shown in Fig. 13, ready for another operation. After the different word pieces forming the typed lines have been properly justified, the frame by which the guides 48 are carried is removed and the typed matter is then photographed in the usual manner.

In the embodiment shown in Fig. 17 the typed matter is prepared as in the other embodiments on a sheet with slits between the different words and is adhesively secured to a supporting member constructed in the manner shown in Fig. 17. This supporting member comprises a U shaped member 86 in which a number of blocks 87 are guided, these blocks being held to the member 86 by turning the edges of said member inwardly at 88 into grooves in opposite sides of the blocks 87. The sheet is adhesively secured to the upper faces of the blocks and is then cut between the lines in the manner described with reference to the other embodiment. Each block is substantially the width of a character so that each work piece will connect a number of blocks corresponding to the number of letters in the word. The word pieces with the blocks may then be shifted longitudinally in the guide member 86 so as to provide the desired spaces between the words. This shifting may be effected in any suitable manner, either by hand or by a justifying mechanism.

From the foregoing it will be seen that there has been provided a method by which typed matter may have the last letters of its lines brought into alignment, this method being particularly advantageous for use for preparing the typewritten matter for photo-engraving. By this method printed matter made from photo-engraving presents a neater and more balanced appearance.

What I claim as my invention and desire to secure by Letters Patent is:

1. A method of preparing typewritten

matter for duplication which employs a plurality of expansible strips each having a typed line thereon, and which consists in holding the letters at the beginning of the lines at points in alignment with each other, engaging the strips at points equi-distant from the ends of the typed lines, and shifting such points into alignment. 70

2. A method of preparing typewritten matter for duplication which employs a plurality of expansible strips each having a typed line thereon, and which consists in arranging said strips with the first letters in alignment, and simultaneously expanding said strips to bring the last letter of each line of typed matter into alignment without destroying the alignment of the first letters of the lines. 75 80

3. A method of preparing typewritten matter for duplication which employs an elastic sheet with typed lines thereon, and which consists in cutting the sheet between the lines to provide elastic strips, and stretching those strips which do not have their last characters in proper positions to bring such characters to the desired positions. 85 90

4. A method of preparing typewritten matter for duplication which employs an elastic sheet with typed lines thereon, and which consists in cutting the sheet between the lines to provide elastic strips, simultaneously stretching those strips which do not have their last characters in proper positions to bring such characters to the desired positions, and simultaneously securing the strips in their adjusted positions. 100 105

5. A method of preparing typewritten matter for duplication which employs a plurality of expansible strips each having a typed line thereon, and which consists in arranging the strips with the first letters in alignment, expanding said strips to bring the last letter of each line of typed matter into alignment without destroying the alignment of the first letters of the lines and securing said strips in their adjusted positions. 110 115

6. A sheet for the purpose described having lines of typed matter thereon, having a series of openings arranged in alignment along the edge of the sheet at the beginnings of the lines, and having an opening at the end of each line by means of which the lines may be individually expanded, said latter openings being the same distance from the ends of their respective lines. 115 120

7. An elastic sheet for the purpose described having lines of typed matter thereon, the first letters of the lines being in alignment and the last letters being out of alignment, inelastic strips secured to opposite edges of the elastic sheet, the strips at the beginnings of the lines having openings equi-distantly arranged from the first let- 125

ters of the lines, and the strips at the ends of the lines having openings equi-distantly arranged from such ends.

8. An elastic sheet for the purpose described having lines of typed matter thereon, the first letters of the lines being in alignment and the last letters being out of alignment, inelastic strips secured to opposite edges of the elastic sheet, the strip at the beginnings of the lines having openings equi-distantly arranged from the first letters of the lines, and the strips at the ends of the lines having openings equi-distantly arranged from such ends and also having openings arranged in a line transversely of the typed lines and parallel with the openings at the beginnings of the lines.

9. The combination with a plurality of expandible strips each having a typed line thereon and an opening at the beginning and at the end of the typed line, the openings at the beginnings of the typed lines being equidistant from such beginnings and the openings at the ends of the typed lines being equidistant from such ends, a support for each strip, and a justifying mechanism for simultaneous action on the several strips.

10. An elastic strip having a typed line thereon and provided with inelastic portions at opposite ends of the typed line, said inelastic portions having openings.

11. The combination of a pair of supporting members, a projection on each member, an elastic strip connecting said projections and having a typed line thereon, and an inelastic piece secured to said strip at the end of the typed line and provided with an opening through which the strip may be stretched to cause the inelastic portion to engage with the adjacent projection.

12. The combination of a plurality of elastic strips arranged in parallelism and each having a typed line thereon, the first letters of the different lines being in alignment, and the last letters being out of alignment, a support for each strip, such supports lying in the same plane, inelastic portions secured to each of the strips adjacent the first letters and having openings equi-distantly arranged from such first letters, inelastic pieces secured to the strips adjacent their last letters and having openings equi-distantly arranged from the last letters, and justifying mechanism for simultaneous action on the several strips.

13. In combination with a frame, two series of projections supported on the frame, and elastic strips each having a line of typed matter thereon, each strip connecting a projection on one series with the corresponding projection of the other series.

14. In combination with a plurality of expandible strips each having a typed line thereon, the beginnings of the lines being in alignment and the ends of the lines being

out of alignment, of mechanism for operating upon the strips to bring the ends of the lines in alignment without destroying the alignment of the beginnings of the lines.

15. The combination with a plurality of strips each having a typed line thereon, the first letters of the lines being in alignment, and mechanism for justifying such lines to bring their last letters in alignment without destroying the alignment of their first letters.

16. The combination of a form comprising a plurality of expandible strips each having a typed line thereon, of means for securing the strips to hold the first letters of each line in alignment, and means for expanding the strips to bring the last letters of the different lines into alignment.

17. The combination with a plurality of expandible strips each having a typed line thereon, means for securing said strips in parallel relation with the first letters of the lines in alignment, mechanism for expanding the strips to bring the last letters of the lines in alignment, and means for securing the strips in their stretched conditions while they are held by the expanding means.

18. The combination of supporting means having two parallel series of projections, a plurality of expandible strips secured to the projections of one series and each having a typed line thereon, the first letters of the lines being in alignment and the last letters being out of alignment, means for expanding the strips to bring the last letters in alignment, and means for securing the strips to the other series of projections in their expanded positions.

19. In combination with a frame, clips mounted on said frame in two series, each clip being provided with a projection, the projections on each series being aligned and parallel with the projections on the other series, a plurality of expandible strips, each removably secured to a projection of one series and having a typed line thereon, means for expanding the strips to bring the last letters of the typed lines in alignment, and means for securing the strips in the expanded positions upon the projections of the other series of clips.

20. In combination with a form used for preparing typewritten matter for duplication and comprising a plurality of extensible strips on which the lines of typed matter are arranged; of means for removably securing the strips at one end, and justifying mechanism for extending such strips to bring the last letters of different lines in alignment.

21. In combination with a plurality of sets of pieces of sheet material arranged on parallel expandible strips, each set having typed matter thereon, of means for removably securing one end of each strip, and justifying mechanism for shifting such

pieces by extending the strips to bring the last letters of different lines in alignment.

22. The combination with a plurality of expansible strips, each having a typed line thereon, and an opening at the end of its typed line, the openings being equidistantly arranged from such ends, supporting means for the strips, and justifying mechanism for stretching the strips through engagement in 10 said openings to bring the last characters of the lines to desired positions.

23. The combination with a plurality of sets of pieces of sheet material, each set having its pieces in a line and having typed

matter thereon, means for supporting said 15 sets of pieces in parallel relation, and justifying mechanism for shifting such pieces to bring the last letters of different lines in alignment.

24. A sheet for the purpose described, having 20 lines of typed matter thereon, having a series of openings arranged in alignment and having means at the end of each line spaced equidistantly from such ends by means of which the lines may be individually 25 expanded when the sheet is cut between the lines.

EDWARD S. SAVAGE.
